DESIGN FOR A DISPENSING TUBE OR SIMILAR ARTICLE

Ralph F. Peo and Earl P. Riner, Buffalo, N. Y., assignors to Houde Engineering Corporation, Buffalo, N. Y., a corporation of New York

Application May 8, 1939, Serial No. 84,875

Term of patent 7 years

To all whom it may concern:

Be it known that we, Ralph F. Peo and Earl P. Riner, both citizens of the United States, and residents of the city of Buffalo, in the county of Erie and State of New York, have invented a new, original, and ornamental Design for a Dispensing Tube or Similar Article, of which the following is a specification, reference being had to the accompanying drawing forming a part thereof.

On the drawing:

Figure 1 is a front elevational view of the dispensing tube illustrating my new design.

Figure 2 is a side elevational view thereof, and Figure 3 is a top plan view thereof.

We claim:

The ornamental design for a dispensing tube or similar article, as shown.

RALPH F. PEO.
EARL P. RINER.
